(57) **CLAIM**

The ornamental design for a suction mirror, as shown, and described.

DESCRIPTION

FIG. 1 is a perspective front view of the suction mirror, shown with a round suction cup cover;
FIG. 2 is a front view of the suction mirror;
FIG. 3 is a rear view of the suction mirror;
FIG. 4 is a left side view of the suction mirror;
FIG. 5 is a right side view of the suction mirror;
FIG. 6 is a top view of the suction mirror;
FIG. 7 is a bottom view of the suction mirror;
FIG. 8 is a perspective rear view of the suction mirror;
FIG. 9 is a perspective front view of the suction mirror, shown with a square suction cup cover;
FIG. 10 is a front view of the suction mirror;
FIG. 11 is a rear view of the suction mirror;
FIG. 12 is a left side view of the suction mirror;
FIG. 13 is a right side view of the suction mirror;
FIG. 14 is a top view of the suction mirror;
FIG. 15 is a bottom view of the suction mirror; and,
FIG. 16 is a perspective rear view of the suction mirror. The broken lines depict environment and form no part of the claimed design.
